L. L. KNOX.

STACK COOLER FOR BLAST FURNACES.

APPLICATION FILED AUG. 4, 1911.

1,101,701.

Patented June 30, 1914.

UNITED STATES PATENT OFFICE.

LUTHER L. KNOX, OF NILES, OHIO, ASSIGNOR TO KEYSTONE BRONZE COMPANY, OF PITTSBURGH, PENNSYLVANIA, A CORPORATION OF PENNSYLVANIA.

STACK-COOLER FOR BLAST-FURNACES.

1,101,701.

Specification of Letters Patent. Patented June 30, 1914.

Application filed August 4, 1911. Serial No. 642,338.

To all whom it may concern:

Be it known that I, LUTHER L. KNOX, of Niles, in the county of Trumbull and State of Ohio, have invented a new and useful 5 Improvement in Stack-Coolers for Blast-Furnaces, of which the following is a full, clear, and exact description, reference being had to the accompanying drawings, forming part of this specification, in which—

10 Figure 1 is a vertical section of a portion of the bosh and stack walls of a blast furnace, showing several of my improved stack coolers in place. Fig. 2 is a plan view of one of the coolers removed. Fig. 3 is a 15 similar view showing a modification. Figs. 4 and 5 are, respectively, cross sections of Figs. 2 and 3, and Figs. 6 and 7 are detail views showing different forms of the water discharge pipe.

20 My invention has relation to coolers for the stack walls of blast furnaces; and is designed to provide a cooler having means of improved character for introducing the cooling liquid thereto and for maintaining 25 an effective circulation of such liquid therein.

In the drawings, the numeral 2 designates a portion of the stack wall of a blast furnace and 3 my improved coolers. These coolers are preferably made of a length 30 (measured circumferentially of the furnace), considerably greater than their width (measured in the direction of the thickness of the stack wall) and are preferably formed with the convexed outer sides 4 and con-

35 caved inner sides 5. They are hollow, providing an inclosed water containing chamber 6. To supply the cooling water a pipe 7 is provided. This pipe is provided at its outer end with means for connection with a

40 suitable supply pipe 8, and extends inwardly into the chamber of the cooler near one end thereof, and is thence bent to extend transversely, as shown at 9, the entire length of the cooler adjacent to the inner concaved

45 side 5 thereof, being provided with a plurality of discharge openings. These openings may be perforations, such as shown at 10 in Figs. 6, or slots, such as shown at 11 in Fig. 7. These openings discharge the 50 water directly against the inner surfaces of

the side wall 5, which is the hottest portion of the cooler. The heated water rises to the upper portion of the cooler and escapes by an outlet connection 12, which preferably communicates with the chamber of the 55 cooler at substantially the highest point thereof. A suitable blow-out or clean-out connection 13 may also be provided.

The coolers may be made in any suitable manner, as by shaped plates or sheets welded 60 together at their edges, the water pipe being placed in position before the joints are closed.

The invention provides a stack cooler having means for discharging the cooling 65 water directly in contact with the portions thereof which are hottest, and insures the maintenance of a constant circulation of water through the cooler. By placing the outlet at the highest point, the formation of 70 steam pockets is avoided.

What I claim is:

1. A stack cooler for blast furnaces, comprising a hollow segmental body having substantially parallel upper and lower surfaces 75 and having a pipe extending into one end portion thereof to a point near its inner wall, and thence extending transversely of the body adjacent to said inner wall to a point near the opposite end, the transverse 80 arm of the pipe having therein a plurality of discharge openings, substantially as described.

2. A stack cooler for blast furnaces, comprising a hollow sheet metal body of seg- 85 mental form with substantially flat upper and lower surfaces and having a pipe extending radially into one end portion thereof to a point adjacent to its inner wall and thence extending transversely ad- 90 jacent to such inner wall substantially the full length of the body, the transverse arm of the pipe having a plurality of discharge openings, substantially as described.

In testimony whereof, I have hereunto set 95 my hand.

LUTHER L. KNOX.
